ROCKET AMUSEMENT RIDE

George F. McGinnis, Los Angeles, Calif., assignor to
Wed Enterprises, Inc., Glendale, Calif., a corporation
of California

Filed Nov. 13, 1967, Ser. No. 9,356

Term of patent 14 years

(Cl. D34—5)

FIG.1

FIG.2

FIG. 1 is a side elevational view of a rocket amusement ride showing my new design; and

FIG. 2 is a top plan view of said rocket amusement ride.

The dominant features of my design reside in those portions shown in full lines.

I claim:

The ornamental design for a rocket amusement ride, substantially as shown and described.
